United States Patent Office

Des. 178,812

Patented Sept. 18, 1956

178,812

AIR CLEANER AND INTAKE SILENCER UNIT OR SIMILAR ARTICLE

Joseph B. Sebok, Dearborn, Mich., assignor to Houdaille
Industries, Inc., Buffalo, N. Y., a corporation of Michigan

Application February 15, 1956, Serial No. 40,181

Term of patent 14 years

(Cl. D14—6)

Fig. 1

Fig. 2

Fig. 3

Fig. 4

Fig. 1 is a front view of an air cleaner and intake silencer unit, or similar article, embodying my new design;

Fig. 2 is a side view of the structure of Fig. 1 taken from the left-hand side of Fig. 1;

Fig. 3 is a bottom plan view of the structure of Fig. 1; and

Fig. 4 is a rear elevational view taken from the left-hand side of Fig. 2.

I claim:

The ornamental design for an air cleaner and intake silencer unit or similar article, substantially as shown.
